UNITED STATES PATENT OFFICE.

HENRY A. ZIOLA, OF TOLEDO, OHIO, ASSIGNOR TO THE SWARTZBAUGH MANUFACTURING CO., OF TOLEDO, OHIO, A CORPORATION.

SWITCH BRACKET.

Application filed October 12, 1925. Serial No. 62,105.

The purpose of this invention has been to devise a simple terminal connection for electric wires of heating devices such as cookers of different types, a connection in which a bracket is employed for supporting the switch controlling the circuit of said wires, said bracket having socket means also for receiving a plug or equivalent part to enable the control of the current intake as well as the current supply.

In effect my device is virtually a switch and terminal bracket providing in a single bracket structure means for controlling the supply of the current to the particular heating means to which the device is employed, and having simple means for the application of the terminal plug or like device for bringing the current to the heating appliance from the main line.

With such a device as I have designed the switch and terminal bracket may readily be applied to different kinds of heating appliances for effective use with any of them.

One of the preferred embodiments of the invention is illustrated in the accompanying drawings from which an understanding of the invention and its merits under conditions of practical use will be had in conjunction with the following detailed description.

In the accompanying drawings:

Figure 1, is a front view of switch and terminal bracket embodying the invention.

Figure 2, is a side view of the same with the bracket body shown in section as secured to a heating appliance.

Figure 3, is a rear view of the device showing more clearly the peculiar terminal block structure and arrangement of terminal connections.

In carrying out my invention I utilize for my bracket construction a casing member 1 having flanges 2 to enable it to be secured to the heating appliance to which the device is to be used. The casing member 1 is formed at its upper end with a boss 3 in which is mounted a conventional type of switch 4 having the turning knob 5. The switch 4 will comprise the usual metal and porcelain parts with contacts, and is secured to the casing member 1 as shown in Figure 3 by means of terminal and fastening bolts 6. These bolts 6 pass through lateral lugs 7 on the inner portion of the casing mem-

ber 1. From the switch wires 8 may lead into the heating appliance 9 to which my device is secured, in order to carry current into said device, whatever it may be. Insulation 10 may be interposed between the base of the switch 4 and the casing member 1 and current intake wires 11 lead to the switch 4 from a terminal block 12 which is attached to the lower portion of the bracket body or casing member 1 by means of a central bolt 13. This terminal block 12 is a block of special construction made of lava and is adapted to be employed in conjunction with different kinds of switch appliances as well as in its adaptation to my switch and terminal bracket hereof.

The terminal block 12 is provided with terminal members 14 which consist of stems passing through the blocks and screw threaded along the bodies thereof. Nuts 15 are applied to said stems and clamp the block 12 at its upper and lower sides, so as to firmly attach the terminal members 14 thereto. Other nuts 16 applied to the upper ends of the terminal members near the adjacent clamping nuts 15 are used to attach the wires 11 to the block 12. Interposed between the block 12 and the outer side of the casing member 1 is insulation comprising a layer 17 of asbestos and one or more layers of mica 18. Attached to the lowermost portion of the casing member 1 as by the rivet 19 is the terminal plug socket 20. This socket partially encloses members of the terminal 14 and receives the usual terminal plug used so much today for heating appliances.

From the foregoing it will be seen that when the heating appliance (see Figure 1) is provided with the socket 20, current will be supplied to the heating appliance 9 according to the adjustment of the switch 4, or cut off. The current passes through the terminal members 14, wires 11, switch 4, wires 8, into the appliance 9.

With my invention all of the parts just referred to excepting the wires 8 and the appliance 9, are assembled in my switch bracket structure so that the switch bracket may be bodily connected to the appliance 9 as by screw bolts 22, or disconnected with great ease or facility. Viewed from the side, switch bracket casing member 1 tapers upwardly from its lower hollow portion hav-

ing the socket 20, to its upper portion upon which is provided the boss 3 which outstands from the tapering structure.

Having thus described my invention what I claim as new and desire to secure by Letters Patent is:

1. A switch and terminal bracket comprising a switch casing member having side walls with lateral attaching means and an outwardly spaced skirt portion open at its rear and bottom, a transversely disposed insulated block having terminal members and secured to the inner face of said skirt, and a controlling switch located in the casing member and connected to said terminals.

2. A switch and terminal bracket comprising a switch casing member having side walls with lateral attaching means and an outwardly inclined skirt portion spaced from the attaching means and open at its rear and bottom, a transverse insulated block carrying terminal members and secured to the inner face of said skirt next the switch casing member by means extending through the skirt and block, and a controlling switch located in the casing member and connected to said terminals.

In testimony whereof I affix my signature

HENRY A. ZIOLA
